CONTAINER FOR PLAYING CARDS

Jacob E. Hurwitz, Brooklyn, N. Y.

Application December 13, 1950, Serial No. 13,410

Term of patent 14 years

(Cl. D34—13)

To all whom it may concern:

Be it known that I, Jacob E. Hurwitz, a citizen of the United States, residing at Brooklyn, New York, in the county of Kings and State of New York, have invented a new, original, and ornamental Design for a Container for Playing Cards, of which the following is a specification, reference being had to the accompanying drawing, forming part thereof.

In the drawing:

Fig. 1 is a perspective view of a container for playing cards, with the bottom of the cover turned to top position, showing my new design.

Fig. 2 is a vertical sectional view, taken on the line 2—2 of Fig. 1, and

Fig. 3 is an exploded view of Fig. 1, showing the cover in upright position over the container.

The rear view of Fig. 1 is similar to illustration shown in the said figure.

I claim:

The ornamental design for a container for playing cards, substantially as shown and described.

JACOB E. HURWITZ.
